UNITED STATES PATENT OFFICE

158,428

CLOCK JACKET

Paula Zwingenberger, New York, N. Y.

Application September 3, 1947, Serial No. 141,189

Term of patent 7 years

(Cl. D42—7)

To all whom it may concern:

Be it known that I, Paula Zwingenberger, a citizen of the United States of America, and resident of the city, county, and State of New York, have invented a new, original, and ornamental Design for a Clock Jacket, of which the following is a specification, reference being had to the accompanying drawing, forming a part thereof, in which

Fig. 1 is a perspective view from the front and slightly from above, of a clock jacket embodying my design, with the back thereof in closed position; and

Fig. 2 is a perspective view from the rear, of the clock jacket shown in Fig. 1, with the back thereof in open position.

I claim:

The ornamental design for a clock jacket, substantially as shown.

PAULA ZWINGENBERGER.
